UNITED STATES PATENT OFFICE

GRAHAM WYLIE JARVIS, OF CHARLOTTESVILLE, VIRGINIA, ASSIGNOR OF ONE-HALF
TO JOHN E. SHEPHERD, OF CHARLOTTESVILLE, VIRGINIA

ADJUSTABLE FUEL BURNING NOZZLE

Application filed January 24, 1928. Serial No. 249,084.

This invention relates to mixing nozzles for fluid fuel burners, and more particularly to oil burner nozzles, though it is noted that the invention is not limited to nozzles for oil burners nor in some respects even to fuel burners.

One object of the invention is to provide a nozzle device of this kind capable of adjustment for effectively varying the width and heating area of the flame.

Another object of the invention is to provide a device of this kind for providing a wide flare to the flame and an inductive action of compressed air or other combustion supporter which will draw the fuel into and from the nozzle.

Another object of the invention is to provide an apparatus or device of this kind which will effect a thorough mixing action of the fuel and combustion supporter and provide a very thin stiff stream of fuel mixture which may be effectively reached by the surrounding air to insure thorough combustion.

Other objects of the invention are to improve generally the simplicity and efficiency of such nozzles and to provide a device or apparatus of this kind which is economical, reliable and lasting in operation, and economical to manufacture.

Still other objects of the invention will appear as the description proceeds; and while herein details of the invention are described and claimed, the invention is not limited to these, since many and various changes may be made without departing from the scope of the invention as claimed in the broader claims.

The inventive features for the accomplishment of these and other objects are shown herein in connection with an improved oil burner nozzle which, briefly stated, includes a tubular compressed-air nozzle-member having therein a transverse spider having passage openings and a central opening, the exterior of said member having thereon an annular wall near the upper end provided with passage slots. A tubular outer wall is received on said member and engages said annular wall to form a lower fuel-inlet space

and an upper discharge space. The upper end faces of said wall and member are upwardly and outwardly beveled to lie in the same conical surface and are spaced apart to form a fuel-jet orifice. A spreader disposed over the inner face is provided with a shank in threaded engagement with said central opening, and a slotted head having a lower conical face parallel with said faces and closely adjustable to said face of the inner member to direct compressed air across said orifice to draw fuel from said orifice and discharge the mixture outwardly and upwardly to feed the flame.

In the accompanying drawings, showing by way of example, one of many possible embodiments of the invention,

Fig. 1 is a side elevation showing the burner assembled;

Fig. 2 is an axial vertical sectional view, partly in elevation, showing the burner assembled;

Fig. 3 is a fragmental axial vertical sectional view, partly in elevation, showing the burner adjusted for a slightly flaring flame;

Figs. 4 and 5 are similar vertical sectional views showing other positions of adjustment of the burner;

Fig. 6 is a plan showing the upper end of the inner tubular member;

Fig. 7 is a side elevation showing a side of the inner member and the fuel passage slots; and

Fig. 8 is a fragmental vertical sectional view, partly in elevation, showing a boiler with the burner located therein.

My improved burner 10 is here shown in combination with a boiler 11 (Fig. 8) having a vertical fire tube 12 and a lower horizontal tube sheet 13 forming a lower combustion chamber 14 in which is disposed the nozzle burner 10, adapted to produce a wide flaring flame just beneath the tube sheet, as will be explained.

It is noted however that the invention is in no way limited to a boiler, as the burner may be used for any purpose desired.

My improved nozzle burner comprises an outer nozzle wall 15 (Fig. 2), and an inner tubular nozzle member 16 formed with an

enlarged angular tool receiving lower end portion 17 and an inner cylindrical opening 18 threaded at the lower end 19 to receive a compressed air supply pipe (not shown).

5 Said opening 18 is upwardly and outwardly bevelled at the upper end face 20 (Fig. 3), and is provided a short distance from the upper end with a transverse spider 21 having a central threaded opening 22 surrounded by 10 an annular series of closely adjacent air passage openings 23.

The exterior face of said nozzle member 16 above said lower end portion 17 is much smaller in exterior diameter than said end portion, 15 and is provided with a wide annular wall 25 near the upper end of slightly greater diameter than the intermediate and upper part of said face, to provide upper and lower fuel spaces 26 and 27 and an upper fuel mixture space. Said annular wall 25 is provided with 20 a series of diagonal passage slots 28 (Figs. 6 and 7) disposed therearound, all inclined in the same direction around the wall, to give a twisting motion to fuel passing from said 25 lower space 27 to the upper space 26.

The outer tubular nozzle wall 15 is received on said inner member 16 against said enlarged portion 17, the lower part of its inner face having threaded connection with 30 the threads 30 of the inner member. The upper portion of said inner face is cylindrical and has substantially fuel-tight engagement with said annular wall 25. The upper face 31 of said nozzle wall is upwardly and outwardly bevelled to lie in the same conical surface with the upper face 20 of the inner nozzle member, and is slightly spaced therefrom to form a thin annular jet orifice 33 communicating with said upper space 26.

40 The intermediate part of said outer wall 15 is provided with a lateral fuel inlet opening 35 communicating with said lower space 27 and receiving the upper threaded end of a fuel supply elbow 36 having exterior threads 45 at its outer end 37 for connection with a pipe or hose (not shown) to a low down tank or other fuel supply.

A spreader screw 40 having a lower threaded shank 41 adjustably disposed in 50 said central opening 22 has its head provided with a lower conical face 42 parallel with said bevelled faces and an upper transverse tool-receiving slot 43 for adjustment. Said head has substantially the same diameter as 55 the outside diameter of the inner tubular member 16 and said conical face 42 may be adjusted close to said bevelled face 20 to direct compressed air from the inner nozzle member across said jet orifice 32 to draw fuel up 60 through said elbow 36, lower space 27, passage slots 28, upper space 26 and jet orifice 33, mix it with the air and discharge the mixture in an outwardly and upwardly flared stream as indicated by the arrows (Figs. 3 65 to 5) to feed the flame.

Said spreader head is adjustable to vary the effective heating area of the flame, and when adjusted close to the bevelled face 20, causes a thin, stiff, widely flaring stream, as indicated by the arrows of Fig. 5 producing a very wide flame of large heating area. Said head, when adjusted further from the face 20, as in Fig. 4, gives a stream less stiff, less widely flaring and more upwardly directed than in Fig. 5, and a flame of smaller heating area. When said head is adjusted still further from the face 20, it gives a stream still less stiff, less widely flaring and more upwardly directed, as indicated in Fig. 3, and a flame of still smaller heating area.

I claim as my invention:

1. In a burner, an outer casing having a lateral fuel inlet opening intermediate its ends, an inner member having a threaded portion screwed into the lower end of the outer casing, said inner member having a fluid passage extending axially from end to end, said inner member having a circumferential fuel channel opposite said inlet portion, said inner member having its upper portion spaced concentrically to the inner wall of the outer casing and having the portion between its channel and upper end fitting closely in the outer casing, said inner member having a helically extending groove leading from the channel to the space at the upper end, and a spreader carried by the inner member and having screw thread adjustment relative to the space between said casing and member, said casing and member having their upper edges beveled to lie in the same inverted frusto-conical surface and the spreader having a like inverted frusto-conical under surface and having a conical upper surface meeting the under surface in a sharp edge.

2. In a burner, an outer casing having a lateral fuel inlet opening intermediate its ends, an inner member having a threaded portion screwed into the lower end of the outer casing, said inner member having a fluid passage extending axially from end to end, said inner member having a circumferential fuel channel opposite said inlet portion, said inner member having its upper portion spaced concentrically to the inner wall of the outer casing and having the portion between its channel and upper end fitting closely in the outer casing, said inner member having a helically extending groove leading from the channel to the space at the upper end, said inner member having a peripheral groove at each end of said diagonal groove, and a spreader carried by the inner member and having screw thread adjustment relative to the space between said casing and member, said casing and member having their upper edges beveled to lie in the same inverted frusto-conical surface and the spreader having a like inverted frusto-conical under surface and having a conical upper

- surface meeting the under surface in a sharp edge.
3. A burner embodying outer and inner tubular members having conically alined upper end faces and having threaded engagement, the outer member having a lateral fuel inlet, the inner member having a circumferential channel and a wall provided with slanting parallel grooves, a screw adjustable relative to the conically alined faces of the said members, the screw having a head formed with opposed upper and lower conical faces and having a diameter substantially equal to the outer diameter of the inner member.
- 15 4. In a burner, an outer casing member having a lateral fuel inlet intermediate its ends, an inner member having a fuel passage from end to end, a circumferential fuel channel communicating with the fuel inlet, an annular wall dividing the said channel and having helical parallel passages, the outer and inner members having threaded engagement; the upper ends of said members having conically alined faces, a spreader screw adjustably connected to the inner member, its head being formed with lower and upper conical faces and being of a diameter substantially corresponding to the outer diameter of the inner member.
- 25 5. In a burner, outer and inner tubular members, the outer member having a lateral fuel inlet, the inner member having a unitary spider provided with ports and a central threaded bore, the inner member also having a circumferential channel opposite the fuel inlet and a wall in said channel having helical parallel slots, a screw in adjustable engagement with the threaded bore, its head having upper and lower opposed conical faces
- 35 and having a diameter substantially equal to the outer diameter of the inner member.
- 40

Signed at Charlottesville, in the county of Albemarle and State of Virginia this 29th day of December A. D. 1927.
